DUST CATCHER

Emile Prat, Paris, France

Application March 28, 1928, Serial No. 265,268,
and in France April 1, 1927

2 Claims. (Cl. 183—80).

The invention relates to mechanism for removing dust contained in gases and more particularly dust carried along in the smoke from a furnace.

5 Various schemes have been resorted to for the elimination of such dust by catch-pockets and by familiar dust eliminating apparatus.

My invention consists of a combination of instrumentalities, which in practice have been 10 found to be highly successful.

The accompanying drawing shows an embodiment thereof.

Figs. 1 and 2 are vertical sections on planes at right angles to each other;

15 Fig. 3 is a plan view in section along line 3—3 of Fig. 1.

A centrifugal blower *a* has inlets *a*₁, *a*₂ at its two ends for the gas coming through the foot *b*₁, of a stack, the upper part of which is shown at *b*.

20 The casing *c* of the blower is of the usual snail type and is placed within the wall of the stack *b* *b*₁. Ordinarily the casings of such blowers extend about one revolution of a spiral, to about the point *d*.

25 In the present case, the casing proper of the blower is extended by extension *e* which conducts the gas around the casing *c* and up through a pipe *f* to the upper part *b* of the stack.

The dust in the gas, by reason of the centrifugal movement induced by the blower *a*, is projected to the periphery of the casing and is carried beyond the point *d* and down into the extension *e*. In some installations, such an extension of the casing has been shaped and used as a catch box for the dust (from which it is removed at 30 intervals).

I have found in practice that thorough precipitation of dust does not take place in such a pocket or catch-box. But by providing a current 35 of the gas to positively take the dust out of the blower casing, the separation effected by such a blower and casing is greatly improved. For this purpose, I provide a pipe *j* communicating with the extension *e* and leading into a centrifugal 40 separator or so-called cyclone *k* of any usual or suitable design, having a vertical axis. A certain quantity of gas is carried with the dust accumulated in the extension *e* and is blown into the cyclone *k* in a descending spiral. The gyratory motion is obtained by directing the pipe *j* tangentially to the periphery of the cyclone *k*, the 45 opening of said pipe into the latter being shown at *g* behind the plane of Figure 1. The top of the cyclone *k* opens at *h* into the foot *b*₁ of the 50 stack so that, as the inlets *a*₁ of the blower *a* also open into said foot *b*₁, the blower withdraws the 55 gas from the cyclone *k* through *h*, *b*₁ and *a*₁, and thereby compels the gas containing dust to pass from the extension *e* and pipe *j* into the cyclone *k*. The dust falls to the bottom of *k* out through 60

the opening *i*, and the cleaned gas passes through *h* back to the blower *a*.

I am aware that a cyclone or gyration chamber has already been employed for separating dust but not in combination with a centrifugal blower having an outlet directed to a cyclone adapted to cause gyration about a vertical axis. It is also known to allow dust to pass from the periphery of a centrifugal blower into a settling chamber, but the latter has not been formed as a cyclone or vertical gyration chamber, the extension not having been led tangentially to the periphery of such a settling chamber.

A better separation of dust can, however, be obtained by the combined action: first of the vertical cyclone *k* adapted to cause gyratory movement of the gas containing dust branched off from the outlet casing of a centrifugal blower, second of the suction from said chamber through the outlet *h* back to the blower, which forces the dust from the extension *e* into the cyclone *k*.

Various modifications of the embodiment illustrated can be made by those skilled in the art without departing from the invention defined in the following claims.

What I claim is:—

1. The combination with a smoke stack of a centrifugal blower enclosed in a casing within the stack with inlets communicating with the lower portion of the stack and with a main outlet leading to the upper part of the stack, of a centrifugal dust separator having a tangential inlet in communication with a small outlet through the casing of the blower and having its gas outlet communicating with the inlet of the blower so that the blower exerts a suction and causes the dust-laden gas to flow through the separator with sufficient velocity and centrifugal effect to separate the dust.

2. The combination with a smoke stack of a centrifugal blower enclosed in a casing within the stack with inlets communicating with the lower portion of the stack and with a main outlet leading to the upper part of the stack, of a centrifugal dust separator located in the lower part of the stack having a tangential admission conduit communicating with a smaller outlet from the lower part of the blower casing and having its outlet into the lower part of the stack so that the blower causes a suction which draws the dust-laden air through the separator with sufficient velocity and centrifugal force to effect a separation of the dust therein.

EMILE PRAT.
